UNITED STATES PATENT OFFICE.

HARVEY L. BEUCLER, OF LAKE PARK, MINNESOTA.

POTATO-CUTTING MACHINE.

Application filed July 12, 1922. Serial No. 574,540.

To all whom it may concern:

Be it known that I, HARVEY L. BEUCLER, a citizen of the United States, residing at Lake Park, in the county of Becker and State of Minnesota, have invented new and useful Improvements in Potato-Cutting Machines, of which the following is a specification.

This invention relates to potato cutters and has for its object the provision of novel automatic feed means designed for use in connection with or as part of the cutting machine disclosed in my own Patent 1,422,781, issued July 11, 1922.

By reference to this prior patent it will be seen that the machine is for the purpose of cutting potatoes into a plurality of pieces for the purpose of providing seed the principal advantage being the rapidity with which the work may be accomplished, the device being power driven.

The object of the present device is to provide power driven automatic feed means for feeding the potatoes to the hopper of the cutter so that manual labor and personal attention of an operator will be unnecessary.

An additional object is the provision of a device of this character which will be simple and inexpensive in manufacture, efficient and durable in use and a general improvement in the art.

With the above and other objects and advantages in view the invention consists in the details of construction to be hereinafter more fully described and claimed and illustrated in the accompanying drawings, in which:

Figure 1 is a side elevation of my machine equipped with the automatic feed means,

Figure 2 is a longitudinal section through the complete machine,

Figure 3 is a plan view,

Figure 4 is an end view,

Figure 5 is a cross section,

Figure 6 is an elevation of the opposite side.

Referring more particularly to the drawings, I have shown my device as comprising a hopper 10 mounted on top of a rectangular frame 11 which includes sides 12 connected by cross bars 13. This frame 11 is supported upon suitable legs 14. The construction is such that the top of the hopper 10 is open, the bottom of the frame is open, and both ends of the frame are open. Located within the hopper is a V-shaped de-

flector 15 which is located centrally thereof and disposed above the frame 11. Secured to lower cross bars 16 which connect the ends of the sides 12 at their lower edges, 60 are guide rods 17 which extend longitudinally of the frame 11.

Journalized transversely of one end of the frame is a shaft 18 which is provided at one end with a pulley 19 adapted to be 65 driven by a belt which is in turn driven by any suitable power device, and which is provided at its other end with a crank 20. The numeral 21 designates a carriage which includes a block 22 movable longitudinally within the frame 11 and provided at its underside with tubular members 23 70 slideable upon the guide rods 17. The ends of the block 22 are formed with intersecting grooves 24 disposed opposite to and in position to conformingly engage upon or against intersecting die strips or blades 25 secured within the open ends of the frame 11. Secured to this block 22 are elongated strips or fingers 26 which are adapted to 80 project beyond the ends of the frame when the carriage is moved by the means to be described.

In order to effect movement of the carriage, I provide a link bar 27 which is 85 pivoted at one end upon the crank 20 and which has its other end formed with an elongated slot 28 through which passes a bolt 29 which passes through the block 22. One side of the frame is provided with an 90 elongated slot 29 through which the bolt operates.

Located at the inner faces of the sides 12 of the frame, at the ends thereof, are upright plates 30 formed with ears or lugs 31 95 pivotally connected with the frame, as shown at 32, and connected with these lugs or ears are coil springs 33 which are also connected with suitable stationary pins or bolts 34 carried by the frame at the intermediate portion thereof. Normally, the springs 33 operate to hold the plates 30 in such position that they converge outwardly with respect to the ends of the frame. All this above described mechanism constitutes part of my 100 allowed application referred to at the beginning of the specification.

In carrying out the present invention I make the hopper 10 of peculiar construction and provide it with automatic feed means. 110 The bottom of the hopper is formed with a V-shaped central portion 35 from which

lead upwardly and outwardly inclined boards or plates 36 which are formed with slots 37 at the outer ends of which are relatively large openings 38 and at the inner 5 ends of which are small laterally extending openings 39. One side wall of the hopper is formed with a chute 40 which facilitates pouring into the hopper the potatoes to be cut.

10 Journaled transversely of the hopper somewhat near the ends thereof are shafts 41 upon which are secured disks 42 which are mounted within the slots 37. Each disk carries upon its periphery a hook 43 and has 15 pivoted upon its side a latch 44 which has one end heavier than the other so as to normally remain in a certain position with respect to the hook. This latch has its end toward the hook formed with a right angular 20 extension 45 bearing against the inner side of the hook, this extension being provided with a lip 46 engaging within the bill of the hook. Secured upon each inclined end portion 36 of the hopper bottom at the juncture 25 of the slot 37 with the large opening 38 is a trip 47 which is located in position to be engaged by the latch 44 when the disk 42 is rotated.

Secured upon the projecting ends of the 30 shafts 41 are sprockets 48 and 49. Secured upon the shaft 18 of the main portion of the machine is a sprocket 50 about which is trained a chain 51 which is also trained over the sprocket 48 under the sprocket 49 and 35 over an idler sprocket 52 mounted upon one side of the hopper.

The operation of the device is as follows:

The pulley 19, and consequently the shaft 40, 18, is driven by any suitable means, whereupon the movement of the crank 20 will result in corresponding movement of the link bar 27 and this will cause the carriage to move back and forth within the frame, the tubular members 23 being guided by the rods 45 17. The potatoes to be cut are poured through the chute 40 into the hopper 10 and owing to the provision of the V-shaped central portion 35 of the bottom of the hopper the potatoes will pass toward the disks 42.

50 When the shaft 18 is rotated the shafts 41 will be correspondingly rotated. At each rotation of each disk 42 the hook 43 thereon will stick into a potato and carry it along upwardly and toward the end of the hopper, 55 the latch 44 being in such position that its lip 46 is within the bill of the hook behind the potato. As rotation continues the latch 44 will strike the associated trip 47 whereupon the latch will be swung which will 60 cause the potato to be forced off from the hook so that it will fall through the opening 38 into the body of the machine. Of course both disks and their associated parts operate in identically the same manner.

As the carriage is reciprocated as above

described, the ends of the block 22 will engage a certain number of potatoes and force them against the die blades 25, the pivoted spring pressed plates 30 operating to press the potatoes from the side so that they will be presented to the die blades in compact formation. Owing to the fact that the ends of the block 22 are grooved for the accommodation of the die blades it will be apparent that the potatoes will be positively cut as they are forced through the die blades or strips. As the block 22 is retracted from the die blades at either end of the frame, the fingers 26 associated with the block will operate to prevent the potatoes from falling through the frame. As the carriage makes its opposite stroke the fingers are retracted which will cause the cut pieces to be scraped off so that they may fall into any convenient receptacles placed at the ends of the device. 85 As both ends of the device are the same and as potatoes are fed into both ends thereof by the action of the feeding disks above described it is apparent that there will be no idle strokes.

From the foregoing description and a study of the drawings it will be apparent that I have thus provided a simply constructed and consequently inexpensive potato cutter having a rapid action and having automatic feed means which will eliminate all necessity for manual operation or personal attention of the operator. Owing to the simplicity of the construction and the fewness of the parts it is apparent that there will be nothing to get out of order so that the device should have a long life.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I claim:

1. In a machine of the character described including cutting means, feeding means comprising a hopper having its bottom formed with slots leading into large and small openings, shafts journaled transversely of the hopper near the ends thereof, drive means for rotating said shaft in opposite directions, disks on said shafts operating within said slots, hooks on said disks adapted to pick up potatoes within the hopper, said hooks operating through said openings during rotation of the disks and means for automatically kicking off the potatoes through the larger openings.

2. In a machine of the character described including cutting means, feeding means comprising a hopper having its bottom formed with slots leading into large and small openings, shafts journaled transversely of the

- hopper near the ends thereof, drive means for rotating said shaft in opposite directions, disks on said shafts operating within said slots, hooks on said disks adapted to 5 pick up potatoes within the hopper, said hooks operating through said openings during rotation of the disks and means for automatically kicking off the potatoes through the larger openings, said means consisting of 10 latch members pivoted upon the disks and engaging within the hooks behind the potatoes, and means for swinging said latch members when said hooks approach said larger openings.
- 15 3. In a machine of the character described including stationary cutting means, a reciprocating plunger cooperating therewith a drive shaft for operating the latter, feeding means comprising a hopper having its bottom 20 formed with slots leading into large and small openings, shafts journaled transversely of the hopper near the ends thereof, drive means associated with said first named shaft and said last named shafts for rotating 25 the latter in opposite directions, disks on said last named shafts operating within said slots, hooks on said disks adapted to pick up potatoes within the hopper, said hooks operating through said openings during rotation of the disks and means for automatically kicking off the potatoes through the larger openings, said means consisting of 30 latch members pivoted upon each disk and formed at one end with a lip engaging within the bill of the hook behind a potato 35 impaled thereon, and a stationary trip mounted upon the bottom portion of the hopper at the juncture of the slot with the larger opening and engaged by the latch during rotation of the disk whereby to force 40 the potato off from the hook.
4. In a machine of the character described including cutting means, feeding means comprising a hopper having its bottom formed with slots, shafts journaled transversely of 45 the hopper, means for rotating said shafts outwardly, disks on said shafts operating within said slots and carrying hooks adapted to pick up potatoes within the hopper and means adjacent said slots for kicking off the 50 potatoes through the slots.

In testimony whereof I affix my signature.

HARVEY L. BEUCLER.
